UNITED STATES PATENT OFFICE.

THOMAS C. DE PONT, OF JOHNSTOWN, PENNSYLVANIA, ASSIGNOR TO THE JOHNSON COMPANY, OF PENNSYLVANIA.

RAIL-JOINT.

SPECIFICATION forming part of Letters Patent No. 633,731, dated September 26, 1899.

Application filed March 31, 1899. Serial No. 711,275. (No model.)

To all whom it may concern:

Be it known that I, THOMAS COLEMAN DUNONT, of Johnstown, in the county of Cambria and State of Pennsylvania, have invented 5 a new and useful Improvement in Rail-Joints, of which the following is a full, clear, and exact description, reference being had to the accompanying drawings, which form a part of this specification.

10 My invention relates to rail-joints, and more particularly to a joint which can be used with advantage in the construction of what is known as "continuous" track in lieu of the welded joints commonly employed.

15 The invention is designed to provide a joint of this character which possesses the essential requisites of lateral rigidity and of tensile strength sufficient to prevent any breakage or shearing of parts when the weather becomes cold enough to tend to longitudinally contract the rails, and thus put them under tension.

20 It is further designed to provide a joint in which the parts are held together under such a state or degree of compression and tension as to effectually guard against any loosening of the parts under the constant vibration to which the rails are subjected and also all chance for play between the different parts 25 of the joint.

30 I have obtained these objects by means of a joint which I have here shown and which I will now proceed to describe.

Referring to the drawings, Figure 1 is a side 35 elevation of my improved rail-joint. Fig. 2 is a transverse section on the line X X of Fig. 1, showing the joint in course of construction. Fig. 3 is a similar view showing the joint when completed.

40 In the figures, A and B designate the track-rails. C, C', C², and C³ are the splice-bars, two upon each side, and D and E represent rivets.

45 In constructing the joint the rails A and B are provided, by the use of a milling-tool, with the smooth surfaces a, b, c, and d, adjacent to the webs, the upper milled surfaces being slightly undercut, or inclined upwardly, while the lower surfaces c and d are in a similar 50 manner somewhat undercut, or inclined

downwardly. The edges of the splice-bars are also machined to provide the smooth joint surfaces a', b', c', and d', which fit, respectively, the surfaces a, b, c, and d. The distances a' to c' and b' to d' should be about 55 one one-hundredth of an inch greater than the distances from a to c and b to d, respectively. By this relative arrangement of distances a considerable expenditure of lateral pressure is required in order to force the 60 splice-bars from the positions shown in Fig. 2 to their final positions. (Shown in Fig. 3.) Said bars are consequently put in such a state of positive compression and the rails in such a condition of altitudinal tension as to effectually guard against any tendency toward looseness under vibration. The contiguous faces or edges of each adjacent pair of splice-bars are also machined to give them the inner rounded portions c and the outer flat surfaces c', so that said bars will roll upon each other in assuming their seated positions under the lateral pressure employed, but when seated will form a close flush external joint. The preparation of the splice-bars and, where 75 possible, the milling of the rails I prefer to have done at a place adjacent to that at which the rails are rolled.

Where the track is to be laid I provide a riveting-machine of any suitable type having 80 the requisite pressure. By means of this machine I first seat the large rivets D, which pass through all four of the splice-bars. This forces the bars to assume their final positions. As many of the smaller rivets E are then 85 seated as are necessary to enable the joint to stand the tensile stress which the rails are liable to receive during the cold weather. Bolts may of course be used in place of the rivets, although I prefer the latter. Owing 90 to the inclined or beveled formation of the surfaces a, b, c, and d, the splice-bars become finally seated in a manner to greatly resist any tendency to separate from or move upon the rail or upon each other, thereby relieving 95 materially the strain upon the rivets and securing the maintenance of the efficiency of the joint if by any reason the rivets should become in part defective. It will also be seen that in the absence of any rivets or auxiliary

fastenings the construction provides for a joint of very considerable security.

The joint herein described may, if desired, be generally used at all the joints in continuous-track construction, but is found especially advantageous for use in track construction wherein welded joints are generally employed at places, such as at intersection of tracks, where by reason of location or otherwise it becomes difficult or impracticable to effect a welded joint. In such instances the desirability of a joint of this character is such as to outweigh the somewhat increased expense due to the milling or machining of the joint faces. With the exception of these machined faces, however, neither the rails nor the splice-bars require any special conformation, being free from tongues, grooves, and the like, and bolts or rivets of the usual character are the only adjuncts which are required.

Having thus described my invention, what I claim as new, and desire to secure by Letters Patent, is—

1. In a rail-joint, the combination with the rails having the under sides of their heads and the upper sides of their base-flanges adjacent to the web, machined to remove the normal incline thereof and to provide flat bearing-faces, of splice-bars having machined flat upper and lower edges and of greater width than the distance between the upper and lower bearing-faces of the rails, whereby as said bars are forced between said faces toward parallelism with the rail-webs, they are put under a condition of altitudinal compression; and are clamped in position between the head and base-flanges of the rails.

2. The combination with the rails having machined upper and lower inclined bearing-surfaces at their joint portions, adjacent to the web, said upper and lower surfaces being slightly undercut in opposite directions of splice-bars having machined edges to fit said bearing-surfaces, and means for securing said bars in a state of altitudinal compression with their machined edges bearing against said machined surfaces.

3. The combination with a pair of rails having inwardly and upwardly inclined finished surfaces, adjacent to their webs, below their

head and tram-members, and inwardly and downwardly inclined finished surfaces adjacent to their webs, above the flange members, of splice-bars having flat machined edges to fit respectively the said surfaces, and means for securing the bars in a state of altitudinal compression with the inner portions of their machined edges fitting the angles formed by the said inclined surfaces and the adjacent portions of the rails.

4. The combination with the rails having the upper and lower machined surfaces adjacent to the webs, of the four splice-bars, two upon each side, each of said bars having one of its edges machined to fit one of the machined surfaces of the rails, and its other edge machined to form a partly-flat and a partly-rounded face to fit a correspondingly-formed face of the contiguous bar, the flat portions of said edges being toward the outer faces of the bars whereby said bars may roll upon each other in moving from an angular to an alined position and will present a close external joint when in the latter position, and means for securing said bars under compression.

5. The combination with the rails having upper and lower machined surfaces adjacent to their webs, of the four splice-bars, two upon each side, having their longitudinal edges machined to fit respectively the said surfaces and the edges of contiguous bars, the large rivets or bolts, each of which passes through all four of said bars and through one of the rails, and the smaller rivets or bolts, each of which passes through two of said bars and one of the rails, and which are seated subsequently to the seating of the large rivets.

6. The combination with the rails having adjacent to their webs, and upon each side thereof, upper and lower flat machined surfaces which slightly recede from each other toward the web, of the splice-bars having machined edges to fit the said surfaces, and means for securing said bars to the rails in a state of altitudinal compression.

In testimony whereof I have affixed my signature in presence of two witnesses.

T. C. DU PONT.
